UNITED STATES PATENT OFFICE.

THURE E. DAHL, OF NEW YORK, N. Y.

DESIGN FOR A BRACKET LANTERN.

Application filed July 21, 1921. Serial No. 486,575. Term of patent 3½ years.

To all whom it may concern:

Be it known that I, THURE E. DAHL, a subject of the King of Sweden, and residing at New York, in the county of New York and State of New York, have invented a new, original, and ornamental Design for a Bracket Lantern, of which the following is a specification, reference being had to the accompanying drawing, forming part thereof.

Fig. 1 is a side view of a bracket lantern, showing my new design.

Fig. 2 is a front plan view of the bracket back.

Fig. 3 is a bottom plan view of the lantern.

I claim:

The ornamental design for a bracket lantern, as shown.

THURE E. DAHL.
